U.S. PATENT DOCUMENTS

D472,480 S * 4/2003 Chung D10/57
D579,800 S * 11/2008 Mobley D10/57

FIG. 1 is a first perspective view of a wireless barbecue thermometer transmitter showing my new design;
FIG. 2 is a second perspective view thereof;
FIG. 3 is a front elevational view thereof;
FIG. 4 is a rear elevational view thereof;
FIG. 5 is a left side view thereof; and,
FIG. 6 is a top plan view thereof.

The broken lines in the drawings illustrate portions of the wireless barbecue thermometer transmitter which form no part of the claimed design.

The diagonal lines in the drawings indicate transparency.
